UNITED STATES PATENT OFFICE.

LEONARD J. SULLIVAN, OF NORTH SYDNEY, NEW SOUTH WALES, AUSTRALIA.

BELT-LACING FASTENER.

1,267,710.

Specification of Letters Patent.

Patented May 28, 1918.

Application filed June 22, 1916. Serial No. 105,239.

To all whom it may concern:

Be it known that I, LEONARD J. SULLIVAN, a subject of the King of England, residing at North Sydney, in the Province of New

5 South Wales, Australia, have invented certain new and useful Improvements in Belt-Lacing Fasteners, of which the following is a specification.

An object of my invention is to provide a 10 fastener by which the rawhide or other lacing generally used in securing the ends of belting together can be clamped and secured at its ends to thus form a connection which will not give or slip as will the ordinary 15 tying connection of the ends of such a lacing.

As the lacing material or strip is generally of rawhide which has an oil dressing, it is very difficult to secure the ends of a lacing by tying the same and thus the usual method 20 resorted to in lacing a belt is to pass the strand of the lacing in a zigzag course to prevent slipping of the lacing and to then perhaps thread the lacing back through certain of the lacing holes and to pass the ends 25 underneath the zigzag extent of the lacing strip after which the ends are tied together, and it is a further object of my invention to provide such a fastener that the ends of the lacing may be clamped and secured against 30 slipping in a manner that the zigzag lacing may be used or several strips of lacing may be passed through the various lacing holes in a looped formation and the ends secured together on the outer sides of the belt, the 35 arrangement of the clamping portions being such that the proper tension of the lacing strip may be obtained and then by tightening the clamp in place, a clamping and binding action is obtained which is increased in 40 its intensity as the ends of the belt may exert a tension to withdraw from the clamping member.

With the above and other objects in view, my invention consists in certain novel features of construction and combinations of parts which will be hereinafter set forth in connection with the accompanying drawings and then pointed out in the claim.

In the drawings:

50 Figure 1 is a longitudinal sectional view on the line 1—1 of Fig. 2.

Fig. 2 is a fragmentary top plan of a section of belt with the device applied thereto.

Fig. 3 is a view in elevation showing the 55 zigzag or cross lacing of a belt.

Fig. 4 is a view similar to Fig. 3 showing

separate strands or lengths of lacing connecting the ends of the belt.

The device comprises the block member 1 which is cored out in its center to have the 60 central rib 2 extending part way up into the cored out portion from the lower side, the ends 3 and 4 of the block being rounded over as is better illustrated in Fig. 1.

This transverse rib 2 has the screw-threaded 65 orifice 5 provided therein and a clamp lock 6 is cut out to receive the rib 2 and is formed at its ends to conform substantially to the curved shape of the interior walls of the ends 3 and 4, this clamp member 6 being 70 provided with the countersunk bored opening 7 which is formed in alinement with the screw-threaded orifice 5 of the rib 2.

A clamp screw 8 is passed through the bored opening and is screwed into the orifice 75 5 and in this way the clamp member 6 may be adjusted in its relative disposition within the cored out portion of the block 1.

In the use of the device, the belt ends 9 and 10 will be provided with the lacing 80 openings 11 and the lacing 12 will be passed therethrough either in the manner shown in Fig. 3 where a single length of lacing is given a zigzag threading through the lacing openings of the two ends and is to be secured 85 at its free end, or a plurality of lengths of lacing may be used as in the disclosure in Fig. 4, these lengths to be connected at their free ends. In securing the lacings, the ends are passed up through the cored out openings of the block 1 and are brought over 90 against the ends 3 and 4, the clamp member 6 is then placed within the cored out portion and the clamp screw 8 is passed through the opening 7 and is screwed into the orifice of 95 the rib 2 which draws this clamp member 6 down against the end of the lacing 12 and clamps the lacing in rigid securement at its ends against the ends 3 and 4 of the block 1.

While I have herein shown and described 100 only one specific form of the invention, it will be understood that various modifications in the construction and arrangement of the parts might be resorted to, to adapt the device for various specific uses, and hence I do 105 not wish to be limited to the exact disclosure, but only to such points as may be set forth in the claim.

I claim:

A belt lacing fastener comprising a block 110 cored out in its central portion and having a transversely extending rib substantially cen-

trally disposed across the lower part of the cored opening, the ends of the block in the cored opening being rounded to receive the end of a belt lacing passed through the opening and to present a broad surface therefor, said rib portion having a threaded opening formed therein, a substantially wedge-shaped clamp member made of a size to fit loosely within the cored opening of the block and having the inner end thereof grooved to receive the rib so that the wedge portion will substantially fill the cored opening, said clamp member having an opening therethrough registering with the screw-threaded

opening of the transversely extending rib, 15 and a clamp screw to be received through the opening of the clamp member and turn the threaded opening of the rib to draw the clamp member down against the ends of the belt lacing as the same are drawn over the 20 ends of the block.

In testimony whereof I affix my signature in presence of two witnesses.

LEONARD J. SULLIVAN.
